United States Patent Office

Des. 221,233
Patented July 20, 1971

221,233

PORTABLE TELEMETRY UNIT

Robert J. Huszar, Hartford, Conn.

Filed May 7, 1970, Ser. No. 22,882

Term of patent 14 years

Int. Cl. D14—03

U.S. Cl. D26—14

FIG. 2

FIG. 4

FIG. 3

FIG. 8

FIG. 1 is a front elevational view of a portable telemetry unit showing my new design;

FIG. 2 is a side elevation thereof;

FIG. 3 is a side elevation as seen from the opposite side;

FIG. 4 is a rear elevation;

FIG. 5 is a top plan view thereof;

FIG. 6 is a front perspective view, taken at a reduced scale;

FIG. 7 is a front elevation of a modified embodiment of the telemetry unit illustrated in FIG. 1; and

FIG. 8 is an end elevation thereof.

The broken lines are shown for illustrative purposes only and do not form part of the claimed design.

I claim:

The ornamental design for a portable telemetry unit, as shown and described.
